UNITED STATES PATENT OFFICE.

ISRAEL BLOCK, OF NEW YORK, N. Y.

DESIGN FOR AN OIL-STOVE.

SPECIFICATION forming part of Design No. 21,650, dated June 21, 1892.

Application filed May 9, 1892. Serial No. 432,518. Term of patent 14 years.

To all whom it may concern:

Be it known that I, ISRAEL BLOCK, a citizen of the United States, and a resident of New York, in the county of New York and State of New York, have invented and produced a new and original Design for Oil and Gas Stoves, of which the following is a full, clear, and exact specification, reference being had to the accompanying drawing, forming part thereof.

10 The invention has relation to a design for an oil and gas stove, and especially to the pedestal or lower part thereof.

In the accompanying drawing, D denotes the central part of the design, which consists 15 of a conventional representation of a harp surrounded by a circular frame, and ornamental open-work with scrolls above and below, all substantially as shown in the drawing.

B B' are circular openings, each surrounded by an upward-converging rim or border of 20 open-work C.

K denotes the outer rim of the pedestal, which is solid, its edges being scalloped, and it is provided with feet E.

What I claim as my invention, and desire to 25 secure by Letters Patent, is—

The design for an oil and gas stove, as shown and described.

Signed at New York, in the county of New York and State of New York, this 2d day of 30 May, 1892.

ISRAEL BLOCK.
